UNITED STATES PATENT OFFICE.

CUTLER D. KNOWLTON, OF BEVERLY, MASSACHUSETTS, ASSIGNOR TO UNITED SHOE MACHINERY CORPORATION, OF PATERSON, NEW JERSEY, A CORPORATION OF NEW JERSEY.

RECIPROCATING ABRADER.

Application filed February 12, 1920. Serial No. 358,054.

To all whom it may concern:

Be it known that I, CUTLER D. KNOWLTON, a citizen of the United States, residing at Beverly, in the county of Essex and State of Massachusetts, have invented certain Improvements in Reciprocating Abraders, of which the following description, in connection with the accompanying drawings, is a specification, like reference characters on the drawings indicating like parts in the several figures.

This invention relates to machines for grinding edge tools. The invention is herein exemplified with particular reference to the grinding or sharpening of the cutting edges of dies such as are employed for cutting out blanks from sheet material. Dies of this character, in plan outline, describe closed figures and usually have abrupt re-entrant angles or corners. They are employed in cutting out shoe soles and uppers, the method of use involving the placing of a die upon a sheet of stock while the latter is supported upon a cutting block, and then forcing the die toward the block to cut out the blank. Obviously if the cutting edge of the die is not uniform some portions thereof will be forced farther into the block than other portions, resulting in unduly marring the surface of the block and sometimes causing the die to become sufficiently stuck to render it difficult to lift the die from the block.

In the manufacture of dies of the character referred to, which are commonly known as "clicking dies", it is customary to abrade both the inner and outer surfaces of the strip of steel to remove the decarbonized skin and to produce or sharpen the cutting edge of the die by grinding the outer or inner face of said edge to a bevel. Owing to the angular form of these dies in plan outline, it is difficult to properly grind the corner portions especially when the bevel is around the inner face of the cutting edge. To act upon the re-entrant angular portions it is customary to employ a file because a wheel, owing to its necessary shaft and driving connections, can not be made to operate in the re-entrant angles unless the wheel be made very small in which case the peripheral speed is insufficient to be effective and the bevel produced would be excessively concave. Furthermore, for the best work, a die of the character referred to should have

the bevelled face of its cutting edge as nearly flat as possible. If filing is effected manually the operation is slow and laborious, and when a power-reciprocated file is employed for any purpose it is necessary to also vibrate or oscillate the file laterally during each stroke so the teeth will operate in one direction and clear the work on the return stroke to avoid distortion of the shape of the cutting teeth. Moreover a file, if used continuously for a material length of time, is liable to overheat the work and become overheated itself and so affect the temper of the die and have its own teeth softened. This liability of overheating exists even when filing slowly because of the increased friction due to the necessity of bearing harder on the work to get any action at all. To re-state the objection to the use of a file it may be said, therefore, that whether operated at high or low speed a file is liable to overheat the work and become overheated. On the other hand a granular abrader composed of such material as corundum, carbondum or emery does the best work at high speed with light pressure against metal because the velocity of the abrading particles aids in carrying them into and through metal without overheating it or being itself affected by heat.

It is to overcome the above explained and other difficulties attendant upon the use of a grinding wheel or a file, or the use of both on a die, that important features of this invention have been developed, an object being to provide a machine capable of uniformly grinding or sharpening either the inner or outer bevelled faces of cutters such as clicking dies, having especial reference to re-entrant angular portions of said dies.

With this object in view, a feature of the invention consists in providing a non-rotary grinding member which is angular in cross-section and is mounted to reciprocate in a straight line, and means herein illustrated as a high-speed pneumatic motor having direct connection with the grinding member whereby it is adapted to reciprocate the latter without shock at a linear velocity substantially approximating the peripheral speed of an effective rotary grinder. By thus reciprocating the grinding member at high speed, a maximum of cutting efficiency will be obtained and tendency of particles

of emery or other abrasive substance to break off from the grinding member is reduced to a minimum. As a result, friction between the grinding member and the work is reduced and overheating of the grinding member is avoided.

The invention is further characterized by the combination, with a grinder of the class described, of an inclined work support surface 10 rounding the grinder and capable of being rotatably adjusted to carry different portions of the work into contact with the grinder without changing the inclination of the work relatively to the grinder. As shown, the work support is in the form of a centrally apertured, disk-like table and is supported by arms of different lengths rising from a ring which is mounted to turn freely within a stationary circular guide. 15 Dies of the type known as clicking dies are so formed that the abrupt angular parts thereof constitute but small portions of the entire cutting edge. A granular abrader having a sharp angle or edge to operate in re-entrant angles of the die would be short-lived if its sharp edge were to be used when not necessary such as on portions of the die not abruptly re-entrant. Therefore another important feature of the invention 20 comprises a grinding member angular in cross section and having its angles of varying degrees of sharpness. In the use of such member, a portion having the sharper angle will only be used when operating on a re-entrant angle of the die.

Further features of the invention including certain details of construction and combinations of parts will now be described with reference to the accompanying drawings and 25 pointed out in the claims.

In the drawings,

Fig. 1 is a perspective view of a mechanism embodying my invention;

Fig. 2 is a side elevation partly broken out or in section; and

Fig. 3 represents a section through the grinder on line 3—3 of Fig. 2.

The illustrated preferred form of the invention comprises a base or standard 12 having suitably secured to its upper end a plurality of bracket arms 13 the upper ends of which support a circular guide in the form of a fixed ring 14. The ring 14 and the arm 13 may consist of a single casting.

An upper ring 15 is mounted upon and suitably secured to the upper face of the ring 14 as by screws 16, an annular recess being formed between the rings 14 and 15 to receive the flange 18 of a rotatively adjustable ring 17, said ring 17 carrying an arm 19 and an upright 20, the latter extending to a height greater than the arm 19.

The work support or table 21 having a central hole 22 is provided with ears 23 pivotally connected by a pin 24 with the

upper end of arm 19. Diametrically opposite the location of the pivotal support 24 are ears 25 depending from the table, said ears receiving between them the upper end of the upright 20, a screw or bolt, having a wing nut 26, being employed to secure the ears 25 relatively to the upright 20. To permit of some adjustment of the inclination of the work table 21, suitable provision is made such as by means of a slot 27 formed in the upright 20, the screw or bolt having the wing nut passing through said slot.

The base or column 12 supports the motor for actuating the grinder. I do not limit myself to any particular motor employed but for reasons hereinafter explained I prefer a pneumatic motor capable of an exceedingly high speed of reciprocation. In the illustrated embodiment of the invention, the cylinder of a pneumatic motor is indicated at 28 and the piston rod thereof at 29. Coupled to the upper end of the piston 29 is the core 30 of a grinder 31 preferably comprising a block of emery triangular in cross section. I do not limit myself to this particular cross sectional shape of the grinder, but prefer it in order to gain access more readily to the re-entrant portions of a clicking die. As indicated in Fig. 3, the three corners of the grinder are not alike. One as at 32 is quite sharp, another as at 33 is comparatively blunt, and the third as at 34 is intermediate as to its degree of bluntness. In other words, while the corner 33 is rounded to the curve of a certain radius, the corner 34 is rounded to the curve of a shorter radius.

When the machine is in operation, the motive fluid being admitted through the conduit indicated at 35, the grinder reciprocates at very high speed in a straight vertical line. The upper end of the grinder is exposed so that when the inner face of the cutting edge of the die is to be ground or sharpened, said die can be dropped over the top of the grinder so that all portions of its blunt edge will be supported by the table. Owing to the fact that the table is mounted so that it can be rotated, the operator can rotate the table and manipulate the die so as to perform the grinding operation progressively along the inner wall of the die and entirely around it, without altering the angle at which the die is ground or sharpened. Of course, some portions of the die can be ground by one of the flat faces of the grinder. When a very acute re-entrant angle is to be ground or sharpened, the table and the work are rotated so that the sharp corner 32 will act in said re-entrant angle. When angular portions less acute, or when an inward curve of the die is to be moved along in contact with the grinder, then the table will be rotated so that the portion of the die to be ground can be shifted into con-

tact with either of the corners 33 or 34 according to the character of the work. Of course, the very sharp corner 32 will only be used when absolutely necessary in order that the utility of the grinder as a whole may be preserved for the greatest possible length of time. That is, the corner 32, and in fact, also the corner 34, will not be used, unless necessary, so as to delay as long as possible the blunting of those corners due to use. The corners, however, are self-sharpened to a considerable extent by the periodic use of the flat adjacent sides of the grinder.

15 I prefer to use a pneumatic tool for the reason that such a tool is capable of operating without undue shock to parts of its own mechanism at a speed so high that its linear velocity will substantially approximate the effective speed of the periphery of a grinding wheel.

Having described my invention, what I claim as new and desire to secure by Letters Patent of the United States is:

25 1. In a machine for grinding dies, an angular non-rotary grinder mounted to reciprocate in a straight path an adjustably inclined die support surrounding the grinder and being rotatably adjustable to bring different parts of a die into contact with different portions of the grinder, and a high speed pneumatic motor having direct connection with the grinder whereby it is adapted to reciprocate the grinder without shock 35 at a linear velocity substantially approximating the effective speed of the periphery of a grinding wheel.

2. A machine of the character described, comprising a grinder, means for reciprocating the grinder in a substantially vertical plane, an inclined work support surrounding the grinder, and means for adjusting said support rotatively.

3. A machine of the character described, 45 comprising a circular guide, a member

mounted to rotate on the guide, an inclined work support secured to the member, and an abrader mounted to reciprocate through an aperture in the work support.

4. A machine of the character described, 50 comprising a circular guide, a rotatable ring mounted to turn on the circular guide, an arm rising from the rotatable ring, an upright of greater height than the arm, an apertured work table supported on the arm 55 and the upright in an inclined position, and an abrader mounted to reciprocate substantially vertically through the aperture.

5. In a machine of the character described, 60 a grinding member having flat sides for grinding the straight portions of a piece of work and having corner portions differing from one another in contour for engagement with different corners of the work, means for reciprocating the grinder, 65 an inclined work support surrounding the grinder, and means for rotatively adjusting the inclined support to bring the different parts of the work into contact with the desired portions of the grinder without changing the bevel produced on the cutting edge of the work.

6. In an abrading machine for operating upon the cutting edges of tool parts, an abrading element, an inclined rotatable 75 work supporting table surrounding the abrading element, and means to vary and to control the angle of inclination of the table.

7. In an abrading machine for operating upon cutting dies, an annular rotatable work supporting table, an abrading element located centrally of the table and extending upwardly above the surface thereof, and means tiltably to position the rotatable table 80 at various angles with respect to the abrading element.

In testimony whereof I have signed my name to this specification.

CUTLER D. KNOWLTON.
